Electric Company, a corporation of New York

Filed Apr. 25, 1962, Ser. No. 69,840

Term of patent 14 years

(Cl. D42—7)

FIG. 4

FIG. 1 is a front perspective view of a clock embodying my new design;

FIG. 2 is a side elevational view of the clock shown in FIG. 1;

FIG. 3 is a cross-sectional view of the clock taken along line 3—3 of FIG. 1; and

FIG. 4 is a rear elevational view of the clock shown in FIG. 1.

The essential features of my design reside in portions shown in full lines.

I claim:

The ornamental design for a clock or similar article, substantially as shown and described.
